UNITED STATES PATENT OFFICE.

LEWIS C. NORRIS, OF BAY CITY, MICHIGAN.

BOOK-HOLDER.

SPECIFICATION forming part of Letters Patent No. 361,316, dated April 19, 1887.

Application filed February 17, 1887. Serial No. 227,937. (No model.)

To all whom it may concern:

Be it known that I, LEWIS C. NORRIS, a citizen of the United States, residing at Bay City, in the county of Bay and State of Michigan, 5 have invented certain new and useful Improvements in Book-Holders; and I do hereby declare the following to be a full, clear, and exact description of the invention, such as will enable others skilled in the art to which it applies to make and use the same.

This invention relates to devices for holding books open and supporting them in position for reading, and for holding cards and other like objects for display; and it consists in certain improvements therein, as will be herein-after fully described, and pointed out in the claims.

My device is illustrated in the accompanying drawings, as follows:

20 Figure 1 is a perspective view of the device, with a book represented in place thereon by dotted lines. Fig. 2 is a side elevation of the device, in which it is shown open, ready to receive a book, by full lines, and in the position 25 it occupies when holding a book by dotted lines.

The device consists of the following parts: a back frame, A, a shelf, B, a cross-bar, B', a back brace, C, a stay-rod, C', and a front 30 presser or holder, D.

The several parts of the device are formed of wire, except the shelf B, which is preferably of wood; but it may be of wire or a metal bar.

35 The back A consists of a piece of wire bent into a rectangular loop, with its lower ends wound into coils a a, and the upper bar of the loop is bent into a small offset, as at a', to receive the back brace.

40 The shelf B is attached to the back by staples b b. (Seen in Fig. 2.)

The cross-bar B' is a wire passing across the back and bent around its side pieces and then down to the shelf B, where it is secured by 45 staples, or otherwise.

The back brace prop or leg C is a simple straight wire, of proper length, looped around the top piece of the back in the offset a.

45 The stay C' is a wire bent in the form of a Y and twisted in the stem or straight part,

leaving a loop at the end of the stem, which loop is bent into the form of an S and embraces the leg or prop C. The object in bending the loop into an S form is to give a bearing at the points 1 and 2, so the stay when 55 down, as shown in the figures, will bind upon the prop, but will be free to be raised up. The arms of the Y-shaped stay are formed with eyes at the end and are attached to the shelf B by staples, leaving the stay free to fold up 60 against the back and carry the prop along with it.

The front presser consists of a wire which extends across the front of the book, and at each end is bent into the general form of a 65 rocker, and then has its ends bent inwardly to form journals d, which are set into the coils a on the lower ends of the wire forming the back.

When the device is holding a book, as in Fig. 1, it rests upon the angles d' of the front 70 presser, and the presser is converted into a lever having its fulcrum at d', its power-point at d, and its weight along the straight rod in front of the book, and hence the weight of the book is the power which forces the presser 75 against the pages and keeps the book open. When a leaf is to be turned, the user pulls the presser away from the front of the book and turns the leaf, and then lets go of the presser and it will at once act against the book.

80 I am aware that book-holders have been made of wire bent into the form of a frame—as, for example, see patent to Hollaway, May 19, 1885, No. 318,253—and I do not claim as my invention such a device as is there shown.

85 What I claim as new is—

1. In a book-holder, the combination, with a back having a shelf to support the book and a prop to hold the back at a proper incline, of the rocking presser D, pivoted to the back 90 and curved so as to have a bearing upon the table and upon the front of the book and so adjusted, as described, as to sustain the weight of the book.

2. In a book-holder, the combination of the 95 back A, formed of wire and having the coils a and offset a', the shelf and cross-rod B B', attached to said back, the prop C, hung in said offset on the back, the stay C', hung on the said shelf and sliding on the said prop, and 100

the presser D, hung to the back and formed substantially as shown and having a bearing on the table and on the front of the book.

3. The combination, with the prop C and 5 the stay C', of the loop c', bent in the form of an S, and having the bearing-points 1 and 2, as and for the purposes set forth.

In testimony whereof I affix my signature in presence of two witnesses.

LEWIS C. NORRIS.
